[57] ABSTRACT

A stereophonic sound reproducing system having left and right audio transducer means arranged relatively close to each other, and a combiner means connected to a stereophonic sound signal source for generating left and right signals R and L and combining the left and right signals R and L to produce a combined left sound signal $L-jR$ and a combined right sound signal $R-jL$ (j representing a complex number coefficient). These combined sound signals $L-jR$ and $R-jL$ are fed to the left and right sound transducer means, thereby stereophonic sound is reproduced.

STEREOPHONIC SOUND REPRODUCING SYSTEM

BACKGROUND OF THE INVENTION

1. Field of the Invention

This invention relates generally to a sound reproducing system, and more particularly to a stereophonic sound reproducing system in which an audio transducer arrangement raising stereophonic effect is extremely suitable for miniaturization.

2. Description of the Prior Art

With conventional stereophonic sound reproducing systems such as stereo tape recorders, stereo record players, FM stereo receivers, and the like, right and left sounds are respectively reproduced by independent audio transducer systems (each transducer system usually consisting of a single or a plurality of speakers) and the right and left audio transducer systems are disposed, for example, about 1 to 5 meters away from each other, thereby to enhance the stereophonic effect. This inevitably increases the size of the speaker system or a space corresponding thereto. To overcome such a defect, a stereophonic sound reproducing system has been proposed in which right and left speaker systems are disposed close to each other, for example, housed in one box or the speaker systems are miniaturized and disposed close to each other. However, in the case of the stereophonic sound reproducing system being such that right and left sound signals are separately supplied to the right and left speaker systems, differences in intensity and in phase between the right and left sounds from the right and left speaker systems which fall on the listener's right or left ear cannot be recognized so much. Accordingly, excellent stereophonic effects having the same realism as produced in the concert hall cannot be expected with such a conventional stereophonic sound reproducing system.

SUMMARY OF THE INVENTION

One object of this invention is to provide a stereophonic sound reproducing system which permits miniaturization of audio transducer systems but produces an excellent stereophonic effect.

Another object of this invention is to provide a stereophonic sound reproducing system which provides an excellent stereophonic effect even when the right and left audio transducers are disposed extremely close to each other.

A further object of this invention is to provide a stereophonic sound reproducing system in which the right and left speakers can be housed in one box.

Still a further object of this invention is to provide a stereophonic sound reproducing system with which sounds produced by the right and left sound speaker systems are combined together to produce the stereophonic effect.

The stereophonic sound reproducing system of the present invention comprises left and right speaker systems disposed close to each other and a combiner circuit for combining together right and left sound signals R and L from a stereophonic signal source to provide sound signals $R - \gamma L$ and $L - \gamma R$, γ being a complex number coefficient to be applied to right and left speaker systems respectively. The right and left speaker systems are disposed at such a distance that the angle between directions of maximum sound pressures of difference sound components $\pm(L' - R')$ reproduced from

the right and left speakers emitting sound components of a wave length corresponding to a practical distance between the human ears may exceed the angle between the ears relative to the center between the right and left speakers.

BRIEF DESCRIPTION OF THE DRAWING

FIG. 1 is a block diagram showing one example of a stereophonic sound reproducing system of this invention;

FIG. 2 is a circuit connection diagram illustrating one example of a combiner circuit employed therein; FIGS. 3 to 7 are schematic diagrams for explaining the present invention;

FIG. 8 is a circuit connection diagram showing a modified form of the combiner circuit exemplified in FIG. 2;

FIGS. 9 to 16 are front views illustrating examples of speaker systems of the stereophonic sound reproducing system of this invention; and

FIGS. 17 and 18 are schematic diagrams showing the speaker systems of FIG. 15 in their installed condition.

DESCRIPTION OF THE PREFERRED EMBODIMENTS

In FIG. 1 there is illustrated one example of a stereophonic sound reproducing system of this invention, which employs as left and right speaker systems separate left and right speakers 2L and 2R for overall range and in which the left and right speakers 2L and 2R are housed in one speaker box 3. Reference numeral 4 indicates a listener, who stays on the central line between the left and right speakers 2L and 2R, namely on the central axis L_0 . Reference numeral 1 designates a stereophonic signal source for generating left and right sound signals L and R, which is such, for example, as a microphone, a tape recorder, a record player, an FM receiver or the like. Reference numerals 5L and 5R

identify left and right channel amplifier sections respectively supplied with the left and right sound signals L and R from the stereophonic signal source 1. The outputs of the left and right channel amplifier sections 5L and 5R are respectively supplied to the left and right speakers 2L and 2R.

In this case, the left and right channel amplifier sections 5L and 5R are partly coupled to each other through a coupling means 6 to provide a combiner circuit 7. First and second sound signals $S_1 = L - \gamma R$ and $S_2 = R - \gamma L$ (γ being a complex number coefficient) are respectively derived from the left and right channel amplifier sections 5L and 5R and are supplied to the left and right speakers 2L and 2R respectively, thus emitting therefrom first and second sounds $S_1' = L' - \gamma' R'$ and $S_2' = R' - \gamma' L'$.

The combiner circuit 7 is of such a circuit construction as depicted, for example, in FIG. 2. In this embodiment the left and right channel amplifiers 5L' and 5R' of the left and right channel amplifier sections 5L and 5R are of the emitter grounded type and the emitters of their transistors Q_L and Q_R are interconnected through a variable resistor 6. The bases of the transistors Q_L and Q_R are respectively supplied with the left and right sound signals L and R to derive the first and second sound signals $S_1 = -(L - \gamma R)$ and $S_2 = -(R - \gamma L)$ from the collectors of the transistors Q_L and Q_R . By altering the resistance value of the variable resistor 6, the

value of the coefficient γ can be changed in a range of $0 < \gamma < 1$.

The first and second sound signals S_1 and S_2 derived from the combiner circuit 7 are respectively amplified by output amplifier circuit such as SEPP amplifier circuits and are then supplied to the left and right speakers.

The aforementioned complex number coefficient $\dot{\gamma}$ is expressed in the form of $\dot{\gamma} = \gamma_r + j\gamma_i$. The real part γ_r and the imaginary part γ_i are respectively $0 \leq |\gamma_r| < 1$ and $0 \leq |\gamma_i| < 1$. It is probable that when the coupling means 6 of the combiner circuit 7 includes resistance, electrostatic capacitance and inductance, $\gamma_r \neq 0$ and $\gamma_i \neq 0$.

In the present invention the distance d_0 ($= \lambda_0/2\sin\theta$) between the left and right speakers emitting sound components of a wavelength λ_0 substantially equal to an auditory sensitive practical distance a between the human ears, that is, the effective distance between the audio sensitive parts of the average listener's ears, namely the distance between speakers 2L and 2R in FIG. 1, is selected such that the angle 2θ (see FIG. 3) between the directions of the maximum sound pressures (effective or mean values of the sound pressures) of difference sound components $\pm(L' - R')$ produced by the left and right speakers 2L and 2R may be greater than an angle $2\theta_a$ between the human ears relative to the center between the left and right speakers 2L and 2R.

Referring now to FIGS. 3 to 7, the operation of the stereophonic sound reproducing system of this invention will hereinbelow be described. In FIG. 3 reference characters SP_L and SP_R indicate the central points of sound sources of the left and right audio speakers.

If $\gamma' = 1 - 2\alpha'$, the first and second sounds S_1' and S_2' emitted from the left and right speakers SP_L and SP_R are expressed as follows:

$$S_1' = L' - \gamma'R' = \alpha'(L' + R') + (1 - \alpha')(L' - R')$$

$$S_2' = R' - \gamma'L' = \alpha'(L' + R') + (1 - \alpha')(R' - L')$$

The following will discuss the first and second sounds S_1' and S_2' having a single frequency of a wavelength λ .

Reference characters L_1 to L_5 and R_1 to R_5 designate circles of sound waves of the left and right speakers SP_L and SP_R respectively. The circles L_1 to L_5 are concentric circles about the left speaker SP_L which are different in radius from adjacent ones by $\lambda/2$ and the circles, for example, L_1 , L_3 and L_5 indicate those positions at which instantaneous sound pressure of the first sound S_1' is at maximum in the positive direction and the circles L_2 and L_4 represent those positions where the instantaneous sound pressure is at maximum in the negative direction. The circles R_1 to R_5 are concentric circles about the right speaker SP_R which are different in radius from adjacent ones by $\lambda/2$ and the circles, for example, R_1 , R_3 and R_5 indicate those positions where instantaneous sound pressure of the second sound S_2' is at maximum in the positive direction and the circles R_2 and R_4 represent those positions at which the instantaneous sound pressure is at maximum in the negative direction.

The sound waves of the first and second sounds S_1' and S_2' interfere with each other. As above described, the first and second sounds S_1' and S_2' respectively include sum sound components $L' + R'$ and difference sound components $\pm(L' - R')$ and the sum sound com-

ponents are of the same phase but the difference sound components are opposite in phase to each other.

Accordingly, the sound pressure (the mean or effective value) of each sum sound component $L' + R'$ is at maximum in the direction in which the intersections of the circles L_1 to L_5 with those R_1 to R_5 are joined together. In this direction the sound pressure (the mean or effective value) of the difference sound components $\pm(L' - R')$ is zero. In the figure black and white circles at the intersections of the circles L_1 to L_5 and R_1 to R_5 respectively indicate those positions where the instantaneous value of the sound pressure of the sum sound component $L' + R'$ is at maximum in the positive and negative directions respectively.

Further, the sound pressure (the mean or effective value) of the difference sound component $L' - R'$ is at maximum in the direction in which the intersections of the circles L_1 to L_4 and R_2 to R_5 are joined together. In this direction the sound pressure (the mean or effective value) of the sum sound component $L' + R'$ is zero. Black and white circles at the intersections of the circles L_1 to L_4 with those R_2 to R_5 respectively indicate those positions where the instantaneous value of the sound pressure of the difference sound component $L' - R'$ is at maximum in the positive and negative directions respectively.

The sound pressure (the mean or effective value) of the difference sound component $R' - L' = -(L' - R')$ is at maximum in the direction in which the intersections of the circles L_2 to L_5 and R_1 to R_4 are joined together. In this direction the sound pressure (the mean or effective value) of the sum sound component $L' + R'$ is zero. Black and white circles at the intersections of the circles L_2 to L_5 and R_1 to R_4 respectively indicate those positions where the instantaneous value of the difference sound component $L' - R' = -(R' - L')$ is at maximum in the positive and negative directions respectively. Reference characters J_{L+R} , J_{L-R} and J_{R-L} respectively designate directivity characteristic curves of the sum sound component $L' + R'$ and the difference sound components $L' - R'$ and $R' - L'$.

The perpendicular bisector of a straight line connecting the left and right speakers SP_L and SP_R will be referred to as the central axis L_0 and the point of the bisector on the straight line connecting the left and right speakers SP_L and SP_R is indicated by 0. The direction of the maximum sound pressure of the sum sound component $L' + R'$ agrees with the central axis L_0 and the directions of the maximum sound pressures of the difference sound components $L' - R'$ and $R' - L'$ pass through the point 0 and are symmetrical with respect to the central axis L_0 at an angle θ thereto.

The angle θ of the maximum sound pressure directions of the difference sound components $L' - R'$ and $R' - L'$ relative to the central axis L_0 is dependent upon the distance d between the left and right speakers SP_L and SP_R and the wavelength λ of the sound waves emitted from the speakers SP_L and SP_R .

Namely, the angle θ of the direction of the maximum sound pressure of the difference sound component, for example, $L' - R'$ relative to the central axis L_0 is such that the phase difference between the difference sound component $L' - R'$ from the left speaker SP_L and that $R' - L' = -(L' - R')$ from the right speaker SP_R may be 180° , namely $\lambda/2$, as described with FIG. 3 and depicted in FIG. 6. Accordingly, the relationship

$\sin\theta = \lambda/2d$ hold among the angle θ , the distance d and the wavelength λ .

By the way, it is said that a man can readily recognize the direction of the source of a sound which is in a frequency range from about 300Hz to 3KHz only. This is owing to the auditory sensitive practical distance a between the human ears.

That is, when we hear a sound whose wavelength is far greater than the auditory sensitive practical distance a between our both ears, even if we turn our heads, the phase difference between sounds falling on our both ears is too small to be recognized by us. Accordingly, it is difficult for us to recognize the direction of the source of a sound whose frequency is lower than approximately 300Hz. Further, when we hear a sound whose wavelength is far smaller than the auditory sensitive practical distance a , even if we turn our heads, the phase difference between sounds falling on our both ears exceeds the wavelength of the sound and is too great to be recognized by us. Accordingly, it is difficult for us to recognize the direction of the source of a sound whose frequency is in excess of about 3KHz. However, even in the case of a sound having a frequency exceeding 3KHz, we can perceive a little the direction of the sound source by turning our heads several times but the case of a sound having a frequency lower than 300Hz, it is difficult for us to perceive the direction of its sound source even by turning our heads many times.

Turning back to FIG. 3, the following description will be made. The distance d between the left and right speakers SP_L and SP_R is selected such that when a listener M stays on the central axis L_0 at a position P where the instantaneous value of the sound pressure of the sum sound $L'+R'$ is at maximum in the positive direction, the angle $2\theta_a$ between the listener's ears relative to the center between the left and right speakers SP_L and SP_R may be smaller than 2θ . In this case, let it be assumed that the wavelength of the sound emitted from each of the speakers SP_L and SP_R is λ_0 which is nearly equal to the auditory sensitive practical distance a between the listener's ears.

Thus, the left ear E_L of the listener M lies between the maximum sound pressure directions of the difference sound component $L'-R'$ and the sum sound component $L'+R'$, while his right ear E_R lies between the maximum sound pressure directions of the sum sound component $L'+R'$ and the difference sound component $R'-L'$. In such a case, when the listener M turns his head to the left and right, instantaneous sound pressures W_L and W_R of sounds (having the aforementioned wavelength λ_0 and a single frequency) falling on his ears E_L and E_R vary as shown in FIGS. 4 and 5 respectively, in which the abscissa x represents the distance in a direction away from the point 0 relative to a broken line circle passing the listener's position P and centering about the point 0 . That is, the variations in the instantaneous sound pressures W_L and W_R with the distance x are of the same phase with respect to the sum sound component $L'+R'$ and are opposite in phase with respect to the difference sound components $L'-R'$ and $R'-L'$.

It will be understood from the foregoing that the stereophonic effect having the same realism as produced in the concert hall is greatly raised by selecting the distance d between the left and right speakers SP_L and SP_R such that the listener's left ear E_L lies between the max-

imum sound pressure directions of the difference sound component $L'-R'$ and the sum sound component $L'+R'$ and the right ear E_R lies between the maximum sound pressure directions of the sum sound component $L'+R'$ and the difference sound component $R'-L'$.

Accordingly, if the distance d_0 ($=\lambda_0/2\sin\theta$) between the left and right speakers for emitting sound components having the wavelength λ_0 substantially corresponding to the auditory sensitive practical distance a between the listener's ears is selected such that the angle 2θ between the maximum sound pressure directions of the difference sound components $\pm(L'-R')$ produced by the left and right speakers may exceed the angle $2\theta_a$ between the listener's ears relative to the center between the left and right speakers, the listener's ears may lie between the maximum sound pressure directions of the difference sound components $L'-R'$ and $R'-L'$ which are the majority of the sound component in the frequency range of about 300Hz to 3KHz that the direction of its sound source can be easily recognized by the human being. This ensures to provide for enhanced stereophonic effect for the sound component of the frequency ranging from approximately 300Hz to 3KHz the direction of whose sound source can be readily perceived by the human being and which greatly affects the stereophonic effect. According to my experiments, the stereophonic effect was greatly enhanced with the angle θ exceeding about 10° .

In the event of employing as the transducer system a compound speaker system consisting of a tweeter, a squawker and a woofer, two squawkers are provided for the left and right channels respectively and the distance therebetween is selected to satisfy the aforementioned condition $d_0 = \lambda_0/2\sin\theta$. Further, two tweeters are also provided for the left and right channels respectively and the distance therebetween is selected to be $d_h = \lambda_h/2\sin\theta$ (λ_h being the wavelength of a sound from the tweeters at the center or lower frequency of its range). With such an arrangement, the maximum sound pressure directions of the difference sound components $L'-R'$ and $R'-L'$ of the sound produced by the left and right channel tweeters are close to those of the difference sound components $L'-R'$ and $R'-L'$ of the sound of the wavelength λ_0 produced by the left and right channel squawkers, thereby to provide for further enhanced stereophonic effect. This is due to the fact that the direction of the source of the sound having a frequency higher than about 3KHz can also be recognized to some extent as previously described. The woofer may be two in number for the left and right channels respectively, (in which case the distance d therebetween is selected to be greater than d_0 , for example, $d_t = \lambda_t/2\sin\theta$, λ_t being the wavelength of a sound from the woofers at the center or lower frequency of its range) but it is also possible to use one woofer, to supply it with a sum signal of the left and right low-frequency components and to place it at a desired position, for example, above, below, forwardly or rearwardly of the listener.

It seems that a man recognizes the coming direction of a sound by perceiving the phase difference between the sound waves at his both ears. This will be explained in connection with FIG. 7. Assume that sound waves of a wavelength λ fall on the left and right ears E_L and E_R at an angle Φ to the central axis L_0 . If the phase difference between the sounds at the left and right ears is

taken as β , the following equation (1) holds as will be seen from the figure.

$$a \sin \Phi = \lambda \cdot \frac{\beta}{2\pi} \quad (1)$$

From this equation the angle Φ is given as follows.

$$\Phi = \sin^{-1} \left(-\frac{\lambda}{a} \cdot \frac{\beta}{2\pi} \right) \quad (2)$$

That is, based upon the phase difference β between the sounds perceived by the left and right ears E_L and E_R , the man recognizes that the sound is coming from in the direction at the angle Φ to the central axis L_0 .

For convenience of explanation, let it be assumed that only the left channel sound signal is supplied to the left and right speakers SP_L and SP_R . As to a sound of an angular frequency ω (the wavelength corresponding thereto is λ), the first and second sound signals S_1 and S_2 respectively bear the following relation to time t .

$$S_1 = L_0 \cos \omega t \quad (3)$$

$$S_2 = -\gamma L_0 \cos \omega t \quad (4)$$

where $0 \leq \gamma < 1$ or $-1 < \gamma \leq 0$ and L_0 is a constant. First and second sounds (sound pressures) S'_L and S'_R produced by the left and right speakers SP_L and SP_R based on the sound signals S_1 and S_2 supplied thereto are as follows:

$$S'_L = L'_x \cos \omega t \quad (3')$$

$$S'_R = -\gamma' L'_x \cos \omega t \quad (4')$$

where L'_x and γ' respectively correspond to L_0 and γ and $0 \leq \gamma' < 1$ or $-1 < \gamma' \leq 0$. Thus, sound fields (sound pressures) S'_L and S'_R near the left and right

ears E_L and E_R are respectively given by the following equations.

$$S'_L = \frac{1-\gamma'}{2} L'_x \cos \omega(t - \tau_x) + \frac{1+\gamma'}{2} \eta_x L'_x \sin \omega(t - \tau_x) \quad (5)$$

$$S'_R = \frac{1-\gamma'}{2} L'_x \cos \omega(t - \tau_x) - \frac{1+\gamma'}{2} \eta_x L'_x \sin \omega(t - \tau_x) \quad (6)$$

where L'_x is a factor of the distance x ($=0$) from the center O between the left and right speakers SP_L and SP_R to the ears, L'_x being decreased with an increase in x and $L'_x < L_0$, τ_x is a delay time in propagation of the sound between the central point O and the listener's position P and is in proportion to the distance x and η_x is a composite coefficient of the difference sound component and is a factor of the distance x and the distance d between the speakers, η_x becoming smaller with an increase in x and greater with a decrease in d and $0 < \eta_x < 1$. The first terms of the equations (5) and (6) are

terms of the sum sound component and the second terms are terms of the difference sound components.

It must be noted here that the sum sound components of the first and second sounds S'_L and S'_R are of the same phase and that the difference sound components are opposite in phase to each other and phased $\pi/2$ apart from the sum sound components, as will be seen from the equations (5) and (6) (refer to FIGS. 4 and 5).

Substituting the following equations into the equations (5) and (6).

$$\frac{1-\gamma'}{2} L'_x = A_x \cos \frac{\beta}{2} \quad (7)$$

$$\frac{1+\gamma'}{2} \eta_x L'_x = A_x \sin \frac{\beta}{2} \quad (8)$$

the equations (5) and (6) are respectively as follows:

$$S'_L = A_x \cos \{\omega(t - \tau_x) - \frac{\beta}{2}\} \quad (5')$$

$$S'_R = A_x \cos \{\omega(t - \tau_x) + \frac{\beta}{2}\} \quad (6')$$

The phase difference between S'_L and S'_R corresponds to β in the equations (1) and (2).

β and A_x are respectively expressed as follows:

$$\beta = 2 \tan^{-1} \left(\eta_x \frac{1+\gamma'}{1-\gamma'} \right) \quad (9)$$

$$A_x = L'_x \frac{\sqrt{(1-\gamma')^2 + \eta_x^2(1+\gamma')^2}}{2} \quad (10)$$

Accordingly, from the equations (1) and (9) the angle Φ is given by the following equation.

$$\Phi = \sin^{-1} \left\{ \frac{\lambda}{a} \cdot \frac{\tan^{-1} \left(\eta_x \frac{1+\gamma'}{1-\gamma'} \right)}{2\pi} \right\} \quad \dots \dots \quad (11)$$

The angle Φ may be referred to as equivalent azimuthal angle. Thus, the following facts will be understood from the equation (11). That is, the angle Φ depends upon the wavelength λ of the sound and increases with an increase in the wavelength λ . Further, the angle Φ depends upon the distance d between the left and right speakers. As d decreases, η_x decreases from 1 to 0, and accordingly Φ becomes smaller.

Let it be assumed that $\Phi = \Phi_0$ when $\gamma' = 0$. This implies that the left channel sound L' of the wavelength λ is emitted from the left speaker only and that the right channel sound R' of the wavelength λ is produced from the right speaker only.

With an increase in γ' within a range of $0 < \gamma' < 1$ the angle Φ gradually exceeds Φ_0 . Namely, the stereophonic sound field becomes expanded. According to my experiments, it has been found preferred that γ' , namely γ' is greater than about 0.5.

Further, the angle Φ gradually becomes smaller than Φ_0 with a decrease in γ' within a range of $-1 < \gamma' < 0$. This implies that the stereophonic sound field becomes narrower.

When the following equation (12) holds,

$$\frac{\lambda}{a} \cdot \frac{\tan^{-1} \left(\gamma_x \frac{1+\gamma^2}{1-\gamma^2} \right)}{x} \geq 1 \dots \dots \dots (12)$$

the direction of a sound cannot be recognized as the phase difference (time lag) between sounds falling on the both ears.

In addition, the following fact will be seen from the equation (10). Assume that the distance d between the left and right speakers and the distance x between the point 0 and the listener are constant. If A_x at the time of $\gamma' = 0$ is taken as A_1 , $A_x < A_1$ at the time of $0 < \gamma' < 1$ and $A_x > A_1$ at the time of $-1 < \gamma' < 0$ because η_x^2 is smaller than 1. That is, the increase and decrease in A_x imply an increase and decrease in the sound pressure level (amplitude, mean value and effective value.).

FIG. 8 shows a modified form of the combiner circuit 7 exemplified in FIGS. 1 and 2. In the present example, the combiner circuit includes a high-pass filter and is adapted not to combine the low-frequency component of a sound the direction of which the human being cannot recognize.

Reference numerals 5L' and 5R' respectively indicate, for example, symmetrical emitter-grounded amplifier of the left and right channel amplifier sections 5L and 5R of FIG. 1 and reference characters Q_L and Q_R amplifying transistors. Reference characters r_1 and r_2 designate emitter resistors of the transistors Q_L and Q_R . The emitter of the transistor Q_L is grounded through a capacitor C_1 and a resistor r_3 , while the emitter of the transistor Q_R is grounded through a capacitor C_2 and the resistor r_4 .

The resistors r_1 , r_2 and r_3 and the capacitors C_1 and C_2 provide a symmetrical high-pass filter HPF. In this case, the cutoff frequency of the high-pass filter HPF is selected, for example, about 300Hz. As a result of this, the complex number coefficient γ for low-frequency components L_t and R_t (lower than 300Hz in this example) of the left and right channel sound signals L and R supplied to the left and right transistors Q_L and Q_R is nearly equal to zero and the low-frequency components L_t and R_t are not combined together by the combiner circuit 7 but are derived as $-L_t$ and $-R_t$ from the collectors of the transistors Q_L and Q_R . The middle- and high-frequency components L_h and R_h (higher than 300Hz in this example) of the left and right sound signals L and R are combined together by the combiner circuit 7 to provide sound signals $-(L_h - \gamma R_h)$ and $-(R_h - \gamma L_h)$ at the collectors of the transistors Q_L and Q_R .

The first and second sound signals S_1 and S_2 derived from the combiner circuit 7 are respectively amplified by output amplifier circuits such as SEPP amplifier circuits and then supplied to the left and right speaker systems respectively.

When the frequency of the signal components combined together by the combiner circuit 7 is nearly equal to the cutoff frequency of the high-pass filter HPF, the coefficient γ becomes such that $\gamma_r \approx 0$ and $\gamma_i \approx 0$ for the signal components but for the signal components of a frequency higher than the cutoff frequency the coefficient γ becomes such that $\gamma_i \approx 0$, $\dot{\gamma} = \gamma_r = \gamma$ and $0 < \gamma < 1$. $\dot{\gamma}$ can be altered by changing the resistance value of the resistor r_3 .

Referring now to FIGS. 9 to 18, several examples of the construction of the speaker system of the stereophonic sound reproducing system of this invention will hereinbelow be described. FIGS. 9 to 16 are schematic

from views of the speaker box 3, in which elements corresponding to those in FIG. 1 are identified by the same reference numerals.

In FIG. 9 there is shown a two-speaker system in which the left and right speakers 2L and 2R for overall range are attached to the front of a speaker box 3.

FIG. 10 shows a three-speaker system in which left and right speakers 2L_T' and 2R_T' for middle- and high-frequency components are attached to the front of the speaker box 3 and a common woofer 2W is located at the bottom of the box 3. In this case, it is possible to house the woofer 2W in a separate speaker box and to place it at any desired position, for example, above, below, forwardly or rearwardly of the listener.

FIG. 11 illustrates a four-speaker system comprising left and right speakers 2L_T' and 2R_T' for middle- and high-frequency components and left and right woofers 2L_W and 2R_W which are all attached to the front of the speaker box 3.

FIG. 12 there is depicted a five-speaker system which has left and right tweeters 2L_T and 2R_T and left and right squawkers 2L_S and 2R_S attached to the front of the speaker box 3 and one woofer 2W placed on the bottom of the box 3.

FIG. 13 illustrates a six-speaker system which comprises left and right tweeters 2L_T and 2R_T and left and right squawkers 2L_S and 2R_S attached to the front of the speaker box 3 and left and right woofers 2L_W and 2R_W attached to both sides of the box 3.

FIG. 14 shows an eight-speaker system provided with four tweeters 2L_{Ta}, 2L_{Tb}, 2R_{Ta} and 2R_{Tb}, left and right squawkers 2L_S and 2R_S and left and right woofers 2L_W and 2R_W which are all attached to the front of the speaker box 3.

FIG. 15 there is depicted a five-speaker system comprising left and right tweeters 2L_T and 2R_T, left and right squawkers 2L_S and 2R_S and one woofer 2W which are all located on the front of the speaker box 3.

For example, $d_h = 5$ cm, $(3.4 \times 10^4)/\lambda_h = 7$ KHz, $d_0 = 23$ cm, $(3.4 \times 10^4)/\lambda_0 = 1.5$ KHz, $d_t = 100$ cm and $(3.4 \times 10^4)/\lambda_t = 340$ Hz in the examples of FIGS. 9 to 15.

In the examples of FIGS. 9 to 15 the speaker box 3 may be mechanically reinforced by interposing a reinforcement plate between adjacent speakers on the front panel of the speaker box 3.

In the case where the left and right speaker systems are compound ones, it is possible to construct the combiner circuit 7 such that $\dot{\gamma}$'s in the first and second sound signals $S_1 = L - \dot{\gamma}R$ and $S_2 = R - \dot{\gamma}L$ are different from each other according to the speakers for different sound ranges. Further, the first and second sound signals S_1 and S_2 derived from the left and right channel amplifier sections 5L and 5R shown in FIG. 1 are supplied to filters and then to the respective compound speakers, if necessary, through power amplifiers.

Turning now to FIG. 16, the present invention will hereinbelow be described as being applied to a quasi-4 channel stereophonic sound reproducing system. The left and right speaker systems, in the present example left and right full-range speakers 2L and 2R are attached to the front of the speaker box 3, and, at the same time, left and right auxiliary speaker systems, in this example left and right full-range speakers 2B_L and 2B_R are attached to both sides of the speaker box 3. The distance d_0 between the left and right speakers 2L and 2R is selected as previously described and the first and second sound signals $S_1 = L - \dot{\gamma}R$ and $S_2 = R - \dot{\gamma}L$

are respectively applied to the speakers 2L and 2R and, further, first and second auxiliary sound signals $S_{B1} = L - kR$ and $S_{B2} = R - kL$ are respectively supplied to the left and right auxiliary speakers 2B_L and 2B_R. The complex number coefficient k is generally independent of the aforementioned complex number coefficient γ . Further, the coefficient k is usually expressed by $k = k_r + jk_i$ and $0 \leq |k_r| < 1$ and $0 \leq |k_i| < 1$. In this case, it is preferred to select the coefficient k to be equal to 1.

FIG. 17 shows the above-described quasi-4 channel stereophonic sound reproducing system in one condition of installation. This is a fragmentary top plan view of the speaker box 3. The speaker box 3 is positioned at a corner formed by walls W₁ and W₂ perpendicular to each other. First and second sounds $S_1' = L' - \gamma'R'$ and $S_2' = R' - \gamma'L'$ from the left and right speakers 2L and 2R are directed to the front of the box 3 and first and second auxiliary sounds from the left and right auxiliary speakers 2B_L and 2B_R are directed toward the front of the box 3 after reflected by the walls W₁ and W₂ respectively. The listener stays in front of the speaker box 3.

FIG. 18 illustrates another condition of installation of the quasi-4 channel stereophonic sound reproducing system, in which the speaker box 3 is placed substantially at the center between substantially parallel walls W₁' and W₂'. 25

In the quasi-4 channel stereophonic sound reproducing system of FIG. 16 first and second auxiliary sounds $S'_{B1} = L' - k'R'$ and $S'_{B2} = R' - k'L'$ from the left and right auxiliary speakers 2B_L and 2B_R are delayed behind the first and second sounds $S_1' = L' - \gamma'R'$ and $S_2' = R' - \gamma'L'$ from the left and right speakers 2L and 2R in space. That is, the presence of the first and second auxiliary sounds S'_{B1} and S'_{B2} which are difference sounds raises the stereophonic effect and the illusion of expansion of the sound reproduced and provides the echo effect. 30

The present invention described in the foregoing provides a stereophonic sound reproducing system which

is simple in construction but extremely high in stereophonic effect.

The foregoing examples are intended as being illustrative and not as limiting the invention specifically thereto and the combiner circuit and the speaker systems may be modified variously. Further, the kind of speakers need not be limited to a specific one.

It will be apparent that many modifications and variations may be effected without departing from the scope 10 of the novel concepts of this invention.

I claim as my invention:

1. A stereophonic sound reproducing system comprising first and second audio transducer means disposed in a common housing and fixed a distance $d_o = \lambda_o/2 \sin \theta$ apart from each other, where λ_o represents the wavelength of a component of the sound produced by said transducers, which wavelength substantially corresponds to the effective distance between the audio sensitive parts of both ears of listeners, and θ represents one-half of the angle between maximum sound pressure directions of difference sound components of right and left sounds produced by said first and second audio transducer means and which have said wavelength λ_o , a stereophonic sound signal source for generating right and left sound signals R and L, a combiner means for combining said right and left signals R and L to produce a combined right sound signal R - γ L and a combined left sound signal L - γ R, γ being a complex number coefficient, a first circuit means for feeding said combined right sound signal to said first audio transducer means and a second circuit means for feeding said combined left sound signal to said second audio transducer means.

2. A stereophonic sound reproducing system as claimed in claim 1 wherein said combiner means includes a high pass filter for combining together only relatively high frequency components of said right and left signals to which listeners can have sense of direction. 40
